UNITED STATES PATENT OFFICE.

JAMES H. BAKER, OF SPRINGFIELD, ILLINOIS.

STEAM-ACTUATED VALVE.

SPECIFICATION forming part of Letters Patent No. 449,868, dated April 7, 1891.

Application filed August 6, 1890. Serial No. 361,234. (No model.)

To all whom it may concern:

Be it known that I, JAMES H. BAKER, a citizen of the United States, residing at Springfield, in the county of Sangamon and State 5 of Illinois, have invented a new and useful Improvement in Steam-Actuated Valves, of which the following is a specification.

My invention relates to improvements in steam force-pumps in which the engine and 10 pump are combined into one machine.

The machine is illustrated by the accompanying drawings, in which—

Figure 1 is a longitudinal section through pump and engine. Fig. 2 is a cross-section 15 through the engine on line xx . Fig. 3 is a horizontal section through the steam-box of the engine. Fig. 4 is a vertical section through the length of the auxiliary valve K. Fig. 5 is a cross-section through the pump, and Fig. 20 6 is a top view of one of the pump-valves.

Similar letters refer to similar parts throughout the several drawings.

The pump is operated in the following manner: Steam from the boiler enters the valve 25 A through the supply-tube B, and acting on the head of the piston in the usual way carries it to the other end of the cylinder. The 30 pump-arm G is attached to the piston-rod H, and moving forward with H is carried against the tappet J or J' just before the piston reaches the end of its stroke. The arm G moves easily on the valve-stem D but when G strikes the tappet J or J' it carries D along till its movement is completed. D is attached 35 to the auxiliary valve K, which in its movement with D uncovers the steam-hole a or a', through which live steam enters the cylinder of chest-piston C. C is thus thrown forward and carries with it the steam-valve A, for A 40 is attached to C by the supply-tube B snugly fitting into an opening in C. A then supplies live steam to the piston-head. The steam-ring F lies on top of valve A and about the tube B and makes a steam-tight joint with 45 A. The steam is exhausted from the other end of the chest-cylinder C by passing through a, c, and b or a', c', and b' into the exhaust-chamber L. It will be noticed that C in its movement covers a' or a entirely. The steam

remaining in the exhaust end of the chest- 50 cylinder beyond a' or a forms a cushion for C, and by its expansive force carries C back past the steam-hole a' or a, when by the movement of the auxiliary valve K the steam at the other end of C is allowed to exhaust 55 through the steam-holes a and b or a' and b', which are periodically connected through the channel c or c' in the auxiliary valve K. In case the engine is cold or the parts stick 60 tightly and C fails to move past a' or a, so that the steam from a' or a may act on C, the arm E, attached to D and moving loosely in a slot 65 in the side of C, strikes against the end of said slot and carries C with it to a point fully past a' or a, from which position the live 70 steam carries it to the end of the stroke and with it the steam-valve A. The arm E is necessary only in such emergencies. In the return movement the action is the same, the reference-letters in the description being re- 75 versed. The arm G is clamped to H by two bolts, and by this means is easily adjusted in place and difficult to work loose. The tappets J and J' are fastened by clamp-screws to D and are adjusted to the distance K is 80 required to move.

I am aware that prior to my invention steam force-pumps have been made with a chest-piston controlling the action of the steam-valve, the chest-piston itself being controlled 85 by the movement of the piston-rod of the engine. I do not therefore claim such a combination, broadly; but

What I do claim, and desire to secure by Letters Patent, is—

1. The combination, in a steam force-pump, of the steam-valve A, having a tube B, steam-ring F, auxiliary valve K, chest-piston C, finger E, valve-stem D, and pump-arm G, substantially as shown and set forth. 90
2. The steam-ring F, in combination with steam-valve A and supply-tube B, substantially as set forth.

JAMES H. BAKER.
